UNITED STATES PATENT OFFICE.

CHRISTIAN A. SCHMIDT, OF NEW YORK, N. Y.

DESIGN FOR FRINGE.

SPECIFICATION forming part of Design No. 13,710, dated March 6, 1883.

Application filed December 29, 1882. Term of patent 7 years.

To all whom it may concern:

Be it known that I, CHRISTIAN AUGUSTUS SCHMIDT, of the city, county, and State of New York, have invented and produced a new and 5 original Design for Fringes, of which the following is a full, clear, and exact description.

Reference is to be had to the accompanying drawing, forming part of this specification, in which the figure represents a portion of my 10 newly-designed fringe.

The leading feature of my design consists in the ornamental arrangement of strands, tufts, and molds shown in the drawing, and hereinafter fully described.

15 A B are two parallel strands, connected at right angles by strands C, and ornamented at the points of intersection by the tufts D. At the strand B the strands C are halved, and the adjacent halves of adjacent strands are brought 20 together and connected by bandings, forming a row of X-shaped strands, E. The halves of the strands are then brought together, and are ornamented at their points of meeting by tufts F. At the tufts F the strands are again halved, 25 and upon the adjacent halves of adjacent

strands are placed ball-molds G, and to the said strands, below the said molds, are attached small tufts H. From the tufts H the strands L hang vertical, and to them, a little below the tufts H, are attached larger tufts I. Upon the 30 strands L, below the tufts I, are placed long molds J, having concaved sides. To the ends of the hanging strands L, below the molds J, are attached tufts K.

The ball-molds G and the elongated molds 35 J may be grooved without departing from my design.

I claim—

The design for a fringe herein shown and described, the same consisting of the right- 40 angled strands A B C, having tufts D, the X-shaped strands E, having tufts F, the vertical strands L, having ball-mold G and tufts H, and the two rows of tufts I K, and the interposed elongated molds J.

CHRISTIAN A. SCHMIDT.
